Primary Examiner — Jae Liang*Assistant Examiner* — Tia Ruth-Renee Polidori(74) *Attorney, Agent, or Firm* — Andrus Intellectual Property Law, LLP(57) **CLAIM**

The ornamental design for a simulative gun cylinder drinkware, as shown and described.

DESCRIPTION

FIG. 1 is a top plan view of my new design for a simulative gun cylinder drinkware;

FIG. 2 is a bottom plan view thereof;

FIG. 3 is a right-side elevation view thereof;

FIG. 4 is a left-side elevation view thereof;

FIG. 5 is a top perspective view thereof; and,

FIG. 6 is a bottom perspective view thereof.

The stippling in the drawings indicates the appearance of brass metal.
